FREIGHT SUPPORT STRUCTURE FOR
TRUCKING VANS AND THE LIKE

Earl W. Shreve, Indianapolis, Ind.

Application June 17, 1949, Serial No. 99,839

2 Claims. (Cl. 105—370)

1

This invention relates to a freight support structure for trucking vans and the like.

It is the primary object of this invention to provide a support structure adapted to have loaded thereupon light and fragile freight thereby separating it from the heavy freight which may also be loaded in the van.

During the normal operations of any transportation agency, all types of freight are tendered for transportation. These types may roughly be classified into two categories, namely the light and bulky "top freight" and the heavy "bottom freight." Where a carrier is loading freight as received, it is necessary that he load both types simultaneously. In so doing, it frequently happens that the heavy freight is carelessly loaded on top of the light and fragile freight thereby crushing and damaging the latter.

It also frequently happens that the heavy freight is carelessly loaded in such a manner that the heavy freight is near the top of the van. This creates a top-heavy condition which has been known in many instances to be the sole cause of serious accidents.

The present invention provides a means of overcoming these serious disadvantages and is conducive to careful loading of freight.

It is a further object of this invention to provide a plurality of independent support structures thereby making it possible for as many or as few to be used as the character of the freight may require. In the event there is a minimum quantity of light and bulky freight, it will be necessary and possible to use but one or two of the supporting decks. On the other hand, if the occasion requires it, all may be used.

It is a still further object of this invention to provide an auxiliary supporting structure or deck which may be used when desired to bridge the space between opposed decks, thereby providing an even larger area of deck surface when needed.

It is a still further object of this invention to provide supporting decks of such construction that they may be folded up when not in use to an out-of-the-way position adjacent the side walls of the van.

The primary feature of the invention resides in the construction of the auxiliary decks, which when disposed horizontally provide additional freight supporting surfaces, and when disposed vertically serve as guards to retain the freight in position on the main deck structures.

The full nature of the invention will be under-

2

stood from the accompanying drawings and the following description and claims:

In the drawings, Fig. 1 is a horizontal section view of the trucking van showing the deck structures in use position.

Fig. 2 is a transverse section view thereof taken on line 2—2 of Fig. 1 in the direction of the arrows.

Fig. 3 is a vertical section view taken on line 3—3 of Fig. 1.

In the drawings 10 and 11 show the side and end walls, respectively, of a trucking van. One of the end walls comprises the hingedly secured doors 12 and 13 to permit entrance into the interior of the van. Extending longitudinally within the van and disposed adjacent the side walls thereof are the opposed freight supporting structures or decks shown generally at 14 and 15. While two such decks are shown in the drawings 10 to be disposed adjacent each side wall of the van, it is to be understood that more than two can be used by reducing the length of each deck. Each deck is preferably of a width less than one-half the width of the interior of the van. When the 25 opposed decks are disposed in horizontal, freight supporting position, an aisle 15a is formed therebetween.

The framework of each of the decks comprises the side members 16 and the end members 17, which are suitably coupled together by the elbows 18 to form a generally rectangular frame. While the frame members are shown to be tubular in the drawings, it is to be understood that they may be formed of any suitable material. In order to form a base upon which the freight can be supported, a plurality of longitudinally and transversely disposed slats 19 and 20, respectively, are secured to the side and end frame members.

The freight supporting decks thus formed are each pivotally secured to the side walls of the van through the use of pipe straps 21. It is, of course, a matter of choice as to how many of these straps should be used, the decision being dependent upon the weight of the decks, the weight of the freight loaded thereon and related matters.

Supporting each deck when in its horizontally disposed, freight supporting position, are the foldable support braces 22. The lower end 23 of each brace is pivotally secured to the outer side member of the deck adjacent its juncture with the elbow. The upper end 24 of each is pivotally secured to the side wall of the van.

The decks will each normally be disposed in an upwardly extending, out-of-the-way position

substantially parallel with the side wall of the van. Each is retained in that position when the van is not in use, when it is to be loaded only with heavy freight, or when a particular deck is not needed because of insufficient light freight, by the hangers 25 to which the outer, side members of the deck are adapted to be removably secured.

The primary feature of the invention, however, rests in the construction of the auxiliary deck structure which is designed to be moved from a position where it serves as a freight retaining wall, to a position where it serves as an additional freight supporting deck. This structure includes T's 26 which are pivotally secured to the outer side member of each main deck, there preferably being one T positioned adjacent each end of the side member inwardly of the elbow.

Suitably secured to each T is a tubular arm 27 having an elongated slot 28 formed in the upper portion of its wall. The extremities of the slot are rounded. Slidably mounted within the arm is the latch bolt 29 to which is threadedly secured the knurled thumb screw 30. A portion of screw 30 is rounded making it possible for it, to be seated within the rounded extremities of the slot. By unscrewing thumb screw 30 a distance sufficient to clear the walls defining the rounded portion the latch bolt may be moved relative to the tubular arm. The bolt has a projection 31 formed on its inner end which is adapted to slip within the aperture 32 formed in the upper face of the side member of the main deck.

When the quantity of light freight is not sufficient to warrant the use of the auxiliary decks, the T's and tubular arms will be disposed in a vertical position relative to the main deck with the projection extending within the above-mentioned aligned apertures (see dotted lines, Fig. 3). The thumb screw will have been tightened to hold the latch bolt in that position so that its projection will be held firmly within the aperture and will not be responsive to the jolts and bounces of the moving van. When in such a vertical position, the auxiliary deck, having as it does a series of longitudinal slats 33, will serve as a guard or retaining wall to prevent the freight deposited on the main deck from falling off thereof.

When the quantity of light freight justifies the use of the auxiliary decks, the thumb screws may be untightened to permit the latch bolts to be moved upwardly until their respective projections are removed from the apertures. At that time the T's may be swung downwardly carrying the auxiliary deck therewith. The same procedure is followed with respect to the opposed auxiliary deck when the tubular arms of each opposed deck are in alignment, the latch bolt carried by either of the opposed arms may be moved outwardly until the bolt has been telescopically inserted within its aligned, opposed arm. At such time the thumb screw is tightened thereby locking the opposed arms together in a common plane with each other and with the main deck. With this construction, the gap between opposed main decks is completely bridged and additional space is thereby provided for the loading of freight.

The invention claimed is:

1. In a trucking van and the like adapted for double deck loading, a pair of opposed coplanar freight supporting decks each having a width

less than one-half the width of the interior of said van and being pivotally secured in spaced relation to opposite van side walls intermediate the top and bottom thereof, said decks being swingable from a horizontal freight supporting position to a position contiguous to the van wall and having foldable support elements connecting their free edges to said respective van walls, and an auxiliary freight supporting deck for each of said first mentioned decks having tubular side members pivotally secured to the free edge of said first mentioned deck, said tubular members having openings in their free edges and a slideable latch bolt movable therein, said latch bolt being adapted to be extended beyond said tubular member to a locking position within the tubular member of an opposed auxiliary deck when said auxiliary decks are swung to a horizontal position, and means retaining said latch bolts in locked condition.

2. In a trucking van and the like adapted for double deck loading, a plurality of opposed, coplanar, freight supporting decks each being pivotally secured to a van side wall adjacent one to the other along each side respectively of the interior of said van, said decks each having a width less than one-half the width of the interior of said van and being adapted to be swung from a horizontal freight supporting position to a substantially vertical position contiguous to a van wall, foldable support elements pivotally connecting the free edges of said decks to said van side walls and a combination auxiliary freight supporting deck and freight retaining wall for each of said first mentioned decks, said auxiliary decks each being pivotally secured to the free edge of said first mentioned decks and being provided with tubular side members having their free ends open, and a sliding latch bolt positioned within each of said tubular members adapted to be inserted within the tubular member of an opposed auxiliary deck when said auxiliary decks are swung to a substantially horizontal position, said latch bolt having locking means adapted to retain it in any adjusted position and being provided with a projection on its inner end, the free end of each of said first mentioned decks having vertically disposed apertures formed therethrough concentric with said tubular members when said members are vertically disposed, said latch bolt projections each being adapted to be extended through their respective apertures to retain said auxiliary decks in vertical freight retaining position, and adjustable locking means for retaining said latch bolt projections within said apertures.
